UNITED STATES PATENT OFFICE.

GENNARO DE BELLIS, OF PHILADELPHIA, PENNSYLVANIA.

SHOWER-BATH DEVICE.

1,383,987.

Specification of Letters Patent.

Patented July 5, 1921.

Application filed November 17, 1919, Serial No. 838,609. Renewed May 17, 1921. Serial No. 470,324.

To all whom it may concern:

Be it known that I, GENNARO DE BELLIS, a citizen of the United States, residing at Philadelphia, in the county of Philadelphia and State of Pennsylvania, have invented 5 certain new and useful Improvements in Shower-Bath Devices, of which the following is a specification.

One object of my invention is to provide 10 a shower bath device which can be quickly and easily manufactured and attached to a bath tub.

Another object is to so construct a shower bath device that it will be readily portable 15 and can be quickly placed upon and removed from a bath tub so that when it is not desired for use it can be stored in a closet or other suitable place and will take up comparatively little room.

20 A further object is to so construct my improved shower device that it can be placed upon a bath tub and will have a portion adapted to extend between the two handles of a faucet and can be readily connected to 25 the outlet nozzle of the faucet.

These objects, and other advantageous ends which will be described hereinafter, I attain in the following manner, reference being had to the accompanying drawings in 30 which—

Figure 1 is a perspective view showing my improved shower device operatively connected to a bath tub and to the faucet of the same,

35 Fig. 2 is an elevational view of my improved shower device; a portion being broken away and shown in sectional view,

Fig. 3 is a transverse section taken on the line 3—3 of Fig. 2, and

40 Fig. 4 is a top plan view of Fig. 2.

Referring to the drawings, 5 represents a bath tub having an upper curved flange 6 of a well known construction and a faucet 7, said faucet having two handles 8 and 9 spaced apart for operating valves to permit hot and cold water to pass outwardly through the common nozzle 10. This faucet is of a well known construction and may be made in various shapes without interfering 45 with the attachment of my invention.

50 My improved shower device includes a bracket arm 11 which has one end attached in any suitable manner to a plate 12. This plate 12 can be made of flexible sheet metal and is of the configuration clearly shown in 55 Fig. 1 which includes a looped end portion

13 which can be slid over the bath tub flange 6 by first swinging the bracket arm 11 into a substantially vertical position and then turning into a substantially horizontal position so that the flange will be projected into the looped end 13. The plate 12 is preferably extended a considerable distance below the bracket arm 11 and is adapted to extend between the hot and cold water portions of 60 the faucet as clearly shown in Fig. 1. The outer end of the bracket arm 11 is provided with a substantially vertical hole 14 which extends entirely therethrough from top to bottom and this hole is made angular in 65 cross section. As illustrated the hole 14 is made square in cross section, as shown in Fig. 3 and is adapted to receive a hollow stem 15 which is screwed on the end of a pipe 16. The hollow stem 15 is also angular 70 in cross section for a portion of its length so as to snugly fit within the hole 14 in the bracket arm 11.

The upper end of the stem 15 has projecting ears 17 adapted to rest on the upper 80 edge of the bracket arm 11 adjacent the hole 14 and thereby keep the hollow stem 15 from falling entirely through the hole 14. The lower end of the hollow stem 15 is reduced in cross sectional thickness and provides a 85 corrugated nipple 18 to permit one end of a flexible hose 19 to be attached thereto; the other end of said hose being adapted to be connected to the common nozzle 10 of the faucet 7. The upper end of the pipe 16 is 90 bent at an angle as shown at 20; said angle being substantially in alinement with the length of the bracket arm 11 and projects over the tub 5. A perforated head 21 is secured to the end portion 22 of the pipe 16; 95 said end portion being bent downwardly substantially parallel with the upright portion 23 of the pipe 16 so that the perforated head 21 which may be made of any usual sprinkling construction, depends so that a 100 person standing under the head 21 will receive a shower bath when either or both of the handles 8 and 9 are turned to permit water to pass through the hose 19, stem 18 and pipe 16.

105 To detach the parts from the tub and faucet, it is merely necessary to remove the hose 19 and the pipe 16 and stem 15 can be readily lifted free of the bracket. After this, the bracket arm 11 can be removed by slightly 110 raising the same so as to free the looped end 13 from the flange 6 of the tub 5.

It will be noted that by making the hole 14 angular in cross section and the stem 15 angular so as to fit the hole 14 that when once placed in position, the pipe 16 will not 5 accidentally turn and the sprinkling head 21 will always be in proper position with respect to the longitudinal center of the tub 5. This device can be quickly attached in a position ready for use and when not in use 10 it can be readily stored in a closet as above stated and will therefore not interfere with the ordinary use of the tub 5.

While I have described my invention as taking a particular form, it will be understood 15 that the various parts of my invention may be changed without departing from the spirit thereof, and hence I do not limit myself to the precise construction set forth, but consider that I am at liberty to make such 20 changes and alterations as fairly come within the scope of the appended claims.

Having thus described my invention, what I claim as new and desire to secure by Letters Patent is:—

25 1. A shower device of the character described including a supported arm having an upright hole; and an upright shower pipe including a portion adapted to freely slide downwardly into said hole, said hole 30 and portion of the pipe having parts adapted to prevent rotation therebetween, said pipe having a hose connecting nipple whereby a hose can be connected to said nipple and to a faucet, and the nipple and pipe can 35 be freely lifted upwardly out of said hole when it is desired to detach the pipe from the bracket, said pipe having a part for limiting the downward movement of said portion of the pipe in said hole; substantially 40 as described.

2. A device of the character described including a supporting bracket having a portion for detachable connection with the upper edge portion of a bath tub, said 45 bracket including an arm adapted to extend over the bottom of said tub and having an upright hole extending therethrough, said hole being angular in cross section; and a

shower pipe having a stem, said stem having its outer surface portion of substantially 50 similar cross sectional contour as the cross section of said hole whereby the stem can freely enter downwardly through said hole and the same to prevent relative rotation 55 between the stem and the arm, said stem having a hose-connecting nipple depending downwardly therefrom below the arm, whereby a hose can be connected to said nipple and to a faucet and the stem and nipple can be freely lifted upwardly out of 60 said hole when it is desired to detach the pipe from the bracket, said pipe having a portion for engagement with said bracket for limiting the downward movement of 65 said pipe relatively to said bracket; substantially as described.

3. A device of the character described including a supporting bracket having a portion for detachable connection with the upper edge portion of a bath tub, said 70 bracket including an arm adapted to extend over the bottom of said tub and having an upright hole extending therethrough; and a shower pipe having a stem, said stem including a portion adapted to freely slide 75 downwardly into said hole, said hole and stem having portions adapted to prevent rotation therebetween, said stem having a hose connecting nipple depending downwardly therefrom below the arm whereby a hose 80 can be connected to said nipple and to a faucet, and the stem and nipple can be freely lifted upwardly out of said hole when it is desired to detach the pipe from the bracket, said pipe having a portion for engagement with said bracket for limiting the 85 downward movement of said pipe relatively to said bracket; substantially as described.

In testimony whereof I have signed my name to this specification in the presence of 90 two subscribing witnesses.

GENNARO DE BELLIS.
